CONTAINER FOR COSMETIC STICKS AND
THE LIKEAndre Janer, Flushing, N. Y., assignor to The
A. J. & K. Company, Incorporated, New York,
N. Y., a corporation of New York

Application April 26, 1934, Serial No. 722,418

5 Claims. (Cl. 206—56)

This invention relates to containers for holding and feeding sticks or pencils of cosmetic materials, such, for example, as lipsticks and the like.

The aim of the invention is to provide a container of this sort having various features of novelty and advantage and which is particularly characterized by its extreme simplicity in construction which makes for ease in assembly and economy in manufacture.

By proceeding in accordance with the present invention, a container is provided having a relatively few number of inexpensive parts which may be assembled with facility, the assembly being maintained in a very simple and effective manner.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawing, wherein is shown one embodiment which the present invention may take:

Figure 1 is a side elevational view of the complete container;

Fig. 2 is a longitudinal central sectional view on an enlarged scale through the container;

Fig. 3 is an exploded view showing, in perspective, the parts through which the lipstick is fed or advanced;

Fig. 4 is a view taken substantially on line 4—4 of Fig. 2, this view showing the lower end of the casing with the operating knob removed; and

Fig. 5 is a transverse sectional view taken on line 5—5 of Fig. 2 and looking in the direction of the arrows.

Referring to the drawing in detail, 10 designates a casing which may be of any suitable size and shape but which is preferably cylindrical. The casing may be formed of any suitable material but, by preference, it is made of a moldable material, such as celluloid, casein, or the like. The upper end of the casing is of reduced diameter and is externally threaded as at 11. 12 designates a cover or cap having internal threads at its open end adapted to cooperate with the external threads 11. Upon the interior periphery of the casing are two spiral grooves or threads 13 which extend from the lower end of the casing, as will be seen from Fig. 4, to a point short of the upper end of the casing. The casing, at the upper end of the threads, has an internal downwardly facing shoulder 14.

The numeral 15 designates generally a rotatable shell mounted within the casing and having, at diametrically opposite sides, longitudinally extending slots 16. This shell or tube, by preference,

is formed by drawing a metal blank to the desired shape, and it has a bottom wall 17 provided with a centrally disposed polygonal opening 18, the opening, in the present instance, being square. When the shell is within the casing, the upper end of the shell engages the shoulder 14 and the bottom wall of the shell is slightly above the lower end of the casing, as shown most clearly in Fig. 2.

The numeral 20 designates generally a cylindrical cup-shaped carrier or follower adapted to receive the lower end of a lipstick 21. At opposite sides of the cup 20 are circumferential slots 22 and 23, the latter of which is longer than the former. The lower end of the cup has a flange 24 and an enlarged opening 25.

The cup-shaped carrier has a sliding fit within the rotatable shell 15 and is caused to rotate with that shell by means of a flat plate 26. This plate is somewhat in the nature of a flat pin, the same having a central bowed portion 27 and end lugs 28. The pin extends generally diametrically through the carrier and has its end lugs 28 extending through the slots 22 and 23 and also through the longitudinally extending slots 16 of the rotatable shell. The extreme ends of the pin or plate 26 are slidably received by the respective guideways or spiral grooves 13 so that, when the shell 15 is rotated, the carrier will rotate therewith and the carrier will be advanced longitudinally of the casing. As previously stated, the slot 23 is longer than the slot 22, the purpose of this arrangement being to permit of the plate 26 to be threaded into position within the carrier.

The numeral 30 designates an operating member or knob which is connected to the shell 15 so as to rotate therewith and which is anchored to the casing for rotation relative thereto in a very simple and effective manner. The knob is also preferably formed of moldable material and is preferably of substantially the same diameter as the lower end of the casing against which it abuts. The knob has a cylindrical boss 31 adapted to rotatably fit within the lower end of the casing. The knob is connected to the cylindrical shell 15 by means of a pin or stud which has a square shank 35 and a head 36. The shank corresponds in size and shape to the opening 18 and is adapted to fit more or less closely therein with the head resting upon the upper surface of the bottom wall 17 of the shell. The knob is provided with an aperture 32 which is initially round and is of a lesser diameter than the greatest cross sectional dimension of the square shank 35. The lower end of the shank is driven into this opening, and when this is done, the edges or corners of the stud will cut into the walls of the opening and thus a close tight interlock is formed between the stud and the operating member.

In order to prevent withdrawal of the tube or

shell 15, together with the parts carried thereby, through the lower end of the casing, an anchor plate 40 is provided. This anchor plate is in the form of a sheet metal washer or disk 5 having an enlarged opening 41 which freely accommodates the shank 35 of the stud. The opening, at opposite sides, has notches 42 adapted to accommodate the blade of a tool, such as a screw driver, when inserting the plate in place. 10 The disk is provided at opposite sides with lugs 43 which are adapted to engage in the lower ends of the respective spiral grooves or threads 13. It will be seen from Fig. 2 that this washer or anchor plate is interposed between the bottom of 15 the shell 15 and the top of the operating member.

To assemble the parts of my improved container, the stud is positioned within the opening 18 in the bottom of the shell 15, and the pin 26 is positioned with its ends extending through the 20 slots 22 and 23 of the carrier 20. The carrier may now be placed within the shell 15 with the ends 28 of the pin extending through the slots 16. The shell and carrier may now be introduced into the casing through the lower end thereof, the ends 25 or lugs 28 of the pin being engaged in the spiral grooves 13 and then the shell being turned so as to advance the pin upwardly in the grooves to an extent where the upper end of the shell engages the internal shoulder 14 of the casing. The anchor plate is now positioned on the lower end 30 of the casing with its lugs or ears engaging in the ends of the grooves 13 and then this anchor plate is turned until it is screwed up against the bottom of the shell. The knob may now be positioned so that the lower end of the shank 35 will 35 engage the upper edge of the opening 32 in the knob. The shank is now forced down into that opening, and to accommodate this operation, the pin is provided with the bowed portion 27 so that 40 a tool may be engaged through the notch in that bowed portion with the head 36 of the stud. When the shank is driven into the knob, the knob will take the final position shown in Fig. 2, and it will be clear that the knob is securely connected 45 against axial and rotary movements relative to the shell but that the shell and knob may rotate as a unit relative to the casing and the anchor plate. The latter, since its ends are engaged in the spiral grooves 13, securely prevents accidental 50 withdrawal of the shell and knob through the lower end of the casing.

It will be seen from the foregoing description, taken in connection with the accompanying drawing, that my improved arrangement provides for 55 a very simple and effective container and one which may be very economically manufactured and, therefore, sold at a relatively low price.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of 70 the scope of the invention which, as a matter of language, might be said to fall therebetween.

I claim as my invention:

1. In a container for lipsticks and the like, a casing having a pair of spirally arranged grooves 75 in its inner surface, a rotatable shell disposed

within said casing and having a pair of longitudinally extending slots, a rotatable carrier disposed within said shell and adapted to have longitudinal movement therein, a pin carried by said carrier and having its opposite ends respectively extending through said slots and engaging in said grooves, an operating member at the lower end of said casing and connected to said shell so as to rotate therewith, and an anchor member interposed between said shell and operating member and screwed into said grooves, said anchor member being stationary with respect to said casing, said shell and operating member being adapted to rotate with respect to said casing and anchor member. 15

2. In a container for lipsticks and the like, a casing having a pair of spirally arranged grooves in its inner surface and opening into the bottom end of the casing, a rotatable shell disposed within said casing and having a pair of longitudinally extending slots, a rotatable carrier disposed within said shell and adapted to have longitudinal movement therein, a pin carried by said carrier and having its ends extending through said slots and engaging in said grooves, an anchor plate having oppositely disposed lugs engaging in said grooves, said plate being screwed against the lower end of said shell, a knob at the lower end of said casing and having its upper end adjacent said plate, and a member connecting said knob to said shell against movement relative thereto, said shell, connecting member, and knob being rotatable as a unit with respect to said casing and anchor member. 25

3. In a container for lipsticks and the like, a casing having a pair of spirally arranged grooves in its inner surface and opening into the bottom end of the casing, a rotatable shell disposed within said casing and having a pair of longitudinally extending slots, a rotatable carrier disposed within said shell and adapted to have longitudinal movement therein, a pin carried by said carrier and having its ends extending through said slots and engaging in said grooves, a flat anchor plate having oppositely disposed lugs engaging in said grooves, said plate being screwed against the lower end of said shell, a knob at the lower end of said casing and having its upper end adjacent said plate, and a stud having a shank of non-circular cross section, said shell having a bottom wall provided with an opening corresponding to said shank and adapted to non-rotatably receive the same, the lower end of said stud being driven into said knob. 50

4. In a container for lipsticks and the like, a casing having a pair of spirally arranged grooves in its inner surface and opening into the bottom end of the casing, a rotatable shell disposed within said casing and having a pair of longitudinally extending slots and also having a bottom wall provided with a centrally disposed square opening, a rotatable carrier disposed within said shell and adapted to have longitudinal movement therein, a pin carried by said carrier and having its ends extending through said slots and into said grooves, an anchor plate having an enlarged central opening and oppositely disposed lugs engaging in said grooves, a knob at the lower end of said casing, said plate being interposed between the lower end of said shell and the upper end of said knob, and a stud having a head and a square shank, said stud extending through said opening in the bottom wall of said shell and having its head resting on said bottom wall, the 70 75

lower end of said shank being driven into said knob.

5. In a container for lipsticks and the like, a casing having a pair of spirally arranged grooves in its inner surface and opening into the bottom end of the casing, a rotatable shell disposed within said casing and having a pair of longitudinally extending slots and also having a bottom wall provided with a centrally disposed square opening, a cuplike rotatable carrier disposed in said shell for longitudinal movement therein and having at diametrically opposite sides circumferentially extending slots one of which is longer than the other, a flat pin having a central bowed portion and end lugs, said pin hav-
- 5
- 10
